CARBURETER.

1,203,601.

Specification of Letters Patent. Patented Nov. 7, 1916.

Application filed February 4, 1914. Serial No. 816,574.

To all whom it may concern:

Be it known that I, WESTON M. FULTON, a citizen of the United States, and resident of Knoxville, Tennessee, have invented a new and useful Improvement in Carbureters, which invention is fully set forth in the following specification.

This invention relates to carbureters for internal combustion engines and particularly for engines which operate most efficiently when more or less vacuum is maintained in the manifold.

In liquid fuel explosive engines designed to be used with carbureters in which the air intake to the carbureter is much smaller than the outlet to the engine manifold, a varying degree of vacuum in the manifold and carbureter normally exists. In this type of carbureter there is a liability of the engine taking too great a charge of explosive mixture into the cylinder, resulting in too high compression with possibility of pre-ignition, particularly if the intake has been made too large.

The object of this invention is to vary the degree of vacuum in the carbureter in compliance with the demands of the engine and maintain practically a predetermined composition of the air and fuel mixture for delivery to the engine. This I accomplish by placing in the carbureter, between the air inlet and delivery outlet, a thermosensitive device in the path of the incoming air and outgoing air and fuel mixture, adapted to automatically maintain a substantially constant difference of temperature between the incoming air and air and fuel mixture and having connection with the air supply valve, thereby automatically varying the degree of vacuum in the carbureter to the demands of the engine.

In order that the invention may be readily understood, certain mechanical expressions of the inventive idea are shown in the accompanying drawings, which are designed merely as illustrations to assist the description of the invention, and not as defining the limits thereof, and in which:—

Figure 1 is a central vertical sectional view, with interior parts in elevation, showing a carbureter provided with my improvements; Figs. 2, 3 and 4 are detail views of parts of the device shown in Fig. 1; Fig. 5 is

a vertical central sectional view showing a slight modification; and Fig. 6 is a vertical end view of the same.

Referring to Fig. 1, the carbureter casing is formed in three sections 1, 2 and 3 adapted to be secured together by bolts or other suitable means, and in general shape has the form of a U-tube. The lower section 1 includes a liquid fuel reservoir 4 of annular shape surrounding one limb of the U-tube, and delivers fuel through a jet 5 into the path of the air to be carbureted. Fuel is supplied to the reservoir 4 through a supply pipe 6 controlled by an adjustable valve 7 carried by one arm of a lever 8 pivoted at 9, the opposite arm of the lever being provided with an annular float 10 for operating the supply valve. 11 is a plug for permitting access to the valve 7. The upper section 3 is provided with a flanged outlet 12 for connecting with the engine manifold, not shown, and a flanged inlet 13 adapted for connection with the air induction pipe 14. Sections 2 and 3 separate on the line A—B, and their walls are provided with bearings 15, 16 for receiving the hubs 17, 18 which are secured to the outer end walls of the vibratory vessels 19 and 20. The ends of the hubs are threaded and receive nuts 21, 22 for securing the hubs to their bearings. The opposing walls of the vessels 19 and 20 are each provided with extensions 23, 24 into which is screwed a connecting rod 25 centrally supported in an opening in the walls of sections 2 and 3 and through which it may play. Two annular shoulders 26 are formed on the connecting rod 25, between which is guided a pair of studs 27 (Fig. 2) carried on a link formed in a bell-crank lever arm 28 pivotally supported on a lug 29 on the wall of section 3. The arm 30 of this lever has a link connection 31 with a butterfly damper 32 which is adapted to close against semi-annular seats 33 formed in the casing wall. To the lower end of bell-crank lever arm 28 is attached a tension spring 34 normally acting to move the arm to the left, the tension being adjusted by a thumb-screw 35 engaging a nut 36 to which one end of the spring is fast.

The liquid fuel supply jet 5 is controlled by a valve 37 on a stem 38 which is pivoted to the end of a member 39 hinged to the cas-

ing wall. Adjustment of the valve 37 is secured by means of a rod 40 having a swivel connection 41 (Fig. 3) with a thumb-screw 42 which engages with a threaded opening 5 in the wall of the section 1. In connection with the spray nozzle or jet 5, and above the same, is located a wire gauze partition 43 for facilitating breaking up the liquid particles of fuel and facilitating vaporization.

10 This partition is preferably made so that it may be removed and cleaned, and to this end a semi-annular section is cut out of the wall of the casing for permitting the circular frame of the gauze partition to be inserted.

15 The frame, as shown, is carried by a semi-circular projection 44 on a semi-annular ring 45 adapted to close the cut-out section in the casing wall, and is provided with bolt holes 46 for fastening the closure to the wall. In

20 Fig. 1, the frame is shown in dotted line position to indicate the manner of inserting or removing it.

25 47 is a throttle valve which is adapted to be connected with means under control of an operator, and 48 and 49 are screw plugs for permitting insertion of thermometers when the device is standardized.

30 Assuming that the parts of the carbureter have been assembled and that the discharge end 12 is connected with an internal combustion engine, the carbureter is to be adjusted in the following manner: Plugs 48 and 49 are removed and thermometers are inserted. One thermometer is to indicate

35 the temperature of the incoming air and the other the temperature of the air and fuel vapor mixture. Valve 37 is adjusted by means of thumb-screw 42 for the particular engine to be used and needs no further manipulation.

40 The liquid fuel is admitted to the float chamber 4 from supply pipe 6 and maintained at a proper level by the float 10 acting on the properly adjusted fuel supply valve 7 through its connection 8. The

45 throttle valve 47 is set partly open and the engine is started, thereby causing a draft of air in the direction of the arrows past the spray nozzle 5, through the mixing chamber 50 and to the engine. In normal position,

50 the butterfly valve 32 is almost closed to restrict the admission of air to a sufficient degree as to cause a partial vacuum to be formed in the mixing chamber 50 when the throttle valve 47 is nearly closed and the engine is running at lowest speed. Under

55 these conditions of reduced pressure, liquid fuel is drawn through the nozzle 5 and sprayed into the mixing chamber through the wire gauze screen. The air is thereby carbureted by the vapor of the volatile liquid and the temperature of the mixture is lowered, owing to the passage of liquid into the vaporous state. The two thermometers are thereby subjected to different

60 temperatures while the engine is in opera-

tion. This difference of temperature between that of the incoming air and the mixture of air and vapor is practically a measure of the ratio of the quantity of vapor to that of the air in the mixing chamber. A mixture of air and fuel vapor of any predetermined composition may thus be maintained in the mixing chamber by keeping the difference in temperature between the incoming air and outgoing mixture of air and vapor substantially constant. Having fixed upon a predetermined difference of temperature between the incoming air and the outgoing mixture, the device is adjusted to maintain this difference for different demands on the carbureter. Previous tests with air and gasoline have indicated that a difference of about 14° C. between the incoming air and outgoing mixture gives satisfactory results.

While the engine is running, the temperatures are noted on the thermometers. Should this difference be less than the one selected for standardizing the carbureter, the temperature in the carbureter is evidently too high and therefore more fuel needs to be sprayed into the mixing chamber. Thumb-screw 35 is therefore turned in a direction to thrust the lever arm 28 to the left to overcome somewhat the force exerted by the expansion of the vessel 20 upon vessel 19. This moves butterfly damper 32 toward closed position, thereby somewhat reducing the pressure in mixing chamber 50. The increased vaporization of the liquid fuel reduces the temperature of the air and vapor mixture. When the predetermined difference of temperature is reached, the device will maintain this difference, whatever may be the temperature of the incoming air, and therefore maintain constant the composition of the explosive mixture. The thermometers are removed and the plugs 48 and 49 are replaced.

If the throttle valve 47 is now opened to create a greater demand on the carbureter, thereby reducing the pressure in the carbureter, the amount of liquid drawn into the mixing chamber will increase. The temperature of the air and vapor mixture is lowered in the mixing chamber, while that of the incoming air remains the same. Element 19 will offer less resistance to the expanding force of element 20 and contract, causing butterfly damper to open wider thereby bringing up the reduced pressure in the mixing chamber and cutting down the fuel supply. This action continues until the proportion of air and vapor again reaches normal and the predetermined difference of temperature and composition of the mixture is restored.

The reverse movement of the throttle valve 47 to reduce the demand on the carbureter causes element 19 to overcome element 20,

thereby moving the damper toward closed position to maintain the proper supply of vapor in the mixing chamber.

Owing to the multiplicity of corrugations 5 in the thermosensitive elements, a slight variation of temperature about either vessel causes an appreciable movement of butterfly damper 32 and quick response to such variation. The composition of the mixture is 10 therefore held between very narrow limits and is practically constant to all variations of the flow of air and of the speed of the engine.

That portion of the air conduit inclosing 15 thermosensitive element 20 and the connecting channel between the same and the mixing chamber 50 are made of sufficient cross-section relatively to that of the chamber 50 so that practically the same degree of vacuum will always exist around the element 20 20 as around the element 19, thus preventing any material difference of pressure to act on the two elements.

When the carbureter is provided with 25 means for keeping the temperature of the incoming air constant, the thermosensitive element 19 may obviously be filled with a liquid to prevent effects of pressure variations and vessel 20 in the air intake side then 30 omitted, leaving the element 19 connected with the butterfly valve 32.

In adjusting butterfly damper 32 with respect to thermosensitive elements 19 and 20 when the carbureter is used with automobile engines, the adjustment is such that the 35 vacuum in the carbureter is always sufficient to draw liquid through nozzle 5 at all engine speeds when the surface of the liquid fuel in the chamber is below the spray nozzle. By this arrangement a lower level of 40 liquid can be kept in the fuel chamber and splashing difficulties largely avoided.

In Figs. 5 and 6, I have illustrated my invention in connection with the puddle type 45 of carbureter in which the air passes over the surface of a puddle of the volatile liquid fuel. The construction and arrangement of the valve operating means is the same as that above described, but the lower section of the 50 carbureter is somewhat modified to form a liquid receptacle 1' closed by a funnel-shaped partition 51 adapted to be supported by its outer screw-threaded rim engaging corresponding threads on the wall of the section 55 1. For the purpose of inserting this partition, lugs 52 may be provided for receiving a tool for screwing it in position. The funnel extension or tube 53 extends down into the liquid fuel chamber sufficiently to insure 60 that the end of the tube always dips below the normal level of the liquid which is maintained practically constant by a float 10 and valve 7, as previously described.

When the engine is not running, the liquid 65 level rests at the line marked gasoline line.

While the engine is running, a certain degree of vacuum is formed above the funnel partition and liquid is drawn up through the funnel tube 53 into the body of the funnel and forms therein a puddle, over the surface 70 of which the air flows in passing through the carbureter and takes up vapor from the liquid fuel. To facilitate this action, the air is caused to flow in a narrow stratum under a partition 54 which may be extended to 75 quite near the surface of the liquid. Should the amount of vapor absorbed by the air stream be greater than the predetermined amount for which the carbureter is calibrated, the temperature of the air and vapor 80 mixture lowers and causes thermosensitive element 19 to contract, thereby opening butterfly damper 32 wider and relieving the vacuum over the surface of the liquid fuel in the funnel. The liquid level lowers, thus 85 exposing less surface to the air and reducing the amount of vaporization of the fuel. When the vapor in the mixture falls below the predetermined amount, the reverse of this operation takes place and the liquid 90 rises to expose a greater vaporizing surface.

What is claimed is:

1. In a carbureter, a conduit one end of which is for connection with an internal combustion engine, a valve located at the inlet end of the conduit to control the volume of air supplied to the conduit, means for spraying liquid fuel into the air in the conduit, and a compound thermosensitive device having a connection with said valve and 95 responsive to the temperatures of the incoming air and the outgoing air mixture for operating said valve to proportion the air supply to the varying fuel supply for maintaining a constant composition of the mixture.

2. In a carbureter provided with a valve-controlled air supply and means for spraying liquid fuel into the air current, thermosensitive means exposed to both the entering 110 air and to the air and fuel mixture for operating said inlet valve whereby a constant composition of air and fuel is delivered by said carbureter.

3. In a carbureter, a conduit one end of 115 which is for connection with an internal combustion engine, a valve located at the inlet end of the conduit to control the volume of air supplied to the conduit, means for introducing liquid fuel into the air in 120 the conduit, and means for effecting the mixture of air and fuel, a compound thermosensitive device having a connection with said valve responsive to the temperature of the incoming air and outgoing air mixture for 125 operating said valve to proportion the air supply to the varying fuel supply for maintaining a constant composition of the mixture.

4. In a carbureter adapted for operation 130

under reduced pressure in connection with internal combustion engines, the combination of a carbureter chamber wherein the air and fuel vapor are mixed, said chamber having an air inlet, and a valve controlled discharge outlet, a valve in said inlet controlling the air supply and a thermostatic device having one member in the path of the air supply and having a connection with the 10 inlet valve and another member in the path of the mixed air and vapor.

5. In a carbureter, a conduit one end of which is for connection with an internal combustion engine, a valve located at the 15 inlet end of said conduit to control the volume of air supplied to the conduit, a compound thermosensitive device having a connection with said valve and consisting of connected thermosensitive elements one of 20 which is exposed to the incoming air and the other to the outgoing air mixture, and adjusting means yieldingly connected to said valve and device for adjusting the carbureter to deliver a predetermined and constant 25 air and fuel mixture.

6. In a carbureter, a U-shaped conduit one branch of which receives air and the other delivers air and fuel mixed, valves in both branches, a fuel reservoir supported on one 30 branch and having a valve-controlled jet opening into said delivery branch, a compound thermosensitive device having thermosensitive elements rigidly connected, one of 35 which is in the inlet branch and the other in the outlet branch, a compound lever connection between the inlet valve and one of said elements, and yielding means for adjusting the position of said valves.

7. In a carbureter adapted for operation 40 under reduced pressure in connection with an internal combustion engine, a casing having an air receiving chamber provided with a valve controlled air inlet and an air and vapor mixing chamber open to said first-named chamber, a compound thermosensitive device one element of which is in the air receiving chamber and the other element is in the mixing chamber, connections between 45 said device and said valve, a liquid fuel supply nozzle delivering into said mixing chamber under the reduced pressure maintained in the latter, and a hand-operated valve controlling said nozzle.

8. In a carbureter adapted for operation

under reduced pressure in connection with 55 an internal combustion engine, a casing having an air receiving chamber provided with a valve controlled inlet and an air and vapor mixing chamber open to the first chamber and having a discharge outlet, a compound 60 thermosensitive device having one element in the air receiving chamber and the other element in the mixing chamber, connections between said elements and with said valve, means for spraying liquid fuel into the mixing chamber and a screen between said means and the last-named element, variations of temperature in the mixing chamber affecting the latter to control the air inlet valve for the purpose described. 70

9. In a carbureter adapted for operation under reduced pressure in connection with internal combustion engines, a casing having an air receiving chamber provided with a valve controlled air inlet and a mixing 75 chamber for air and fuel vapor having a discharge outlet and opening into the first-named chamber, a compound thermosensitive device having a vibratory element in the air receiving chamber and another vibratory 80 element in the mixing chamber, a rigid connection between their movable ends and lever connections between said rigid member and said valve, and means for applying an adjustable yielding pressure to said rigid 85 connection for the purpose described.

10. In a carbureter operated under reduced pressure, a source of fuel supply, a conduit admitting air to the mixing chamber of said carbureter, thermosensitive 90 means in the mixing chamber unresponsive to variations of pressure therein, and devices operatively connected to said thermosensitive means to decrease the air supply passing through said conduit on a rise of temperature in the mixing chamber and to increase said air supply on a lowering of said temperature, whereby a constant composition of the air and fuel mixture is maintained under varying demands on the carbureter. 100

In testimony whereof I have signed this specification in the presence of two subscribing witnesses.
